AXIAL FLOW FAN OR PUMP

Friedrich Schicht, Dresden, Germany

Application March 31, 1934, Serial No. 718,442
In Germany May 5, 1933

5 Claims. (Cl. 230—120)

This invention relates to axial flow fans or pumps and particularly to rotary fans or pumps by means of which pressures of the same order of magnitude may be obtained as with centrifugal fans and pumps. The structural arrangement of pumps is similar to that of fans, and in the following description reference will be made only to fans to which the invention is particularly applicable.

10 An object of this invention is substantially to reduce the weight and dimensions of a fan or pump as compared with the weight and dimensions of the usual centrifugal fans or pumps, this feature being of particular importance when 15 large quantities of fluid must be delivered.

Another object of this invention is to provide a new fan or pump which with the same peripheral velocity of the blade-carrying rotor as in the usual axial fans, will produce pressures of 20 the order of 39½ inches of water column, i. e., many times greater than the usual axial fans.

Another object of this invention is to provide a new fan or pump which will be silent in 25 operation and simple in manufacture.

Another object of this invention is to provide a new fan or pump wherein the required energy 30 will attain its maximum value in the neighborhood of the highest efficiency of the fan and will be somewhat reduced by throttling and when a full quantity of fluid is propelled.

These objects are attained by so shaping the surfaces of the rotor wheel hub, the annulus surrounding it, and the surfaces of the blades, 35 that the forces which the rotor wheel exerts on the fluid to be conveyed increase only the speed at normal load without any change of pressure. I have found that a high degree of efficiency can be attained only if this condition is exactly fulfilled in all cross-sections of the rotor wheel.

40 This is the case when a definite relation is established between the tangent led to each rotor blade and the corresponding cross-section of the rotor channel or passage.

Let

 Q = quantity of air, ω = angular velocity.F₀ = cross-sectional area of an annulus at the entrance of the channel,

F = cross-sectional area of an annulus of the section of the channel under consideration,

r = radius of a coaxial cylindrical surface intersecting the blades and substituting for C the expression

10

$$\frac{Q^2}{2\omega} \cdot \left(\frac{1}{F^2} - \frac{1}{F_0^2} \right) = C$$

I get the angular coefficient of a tangent led to the blades $t g \alpha$ in the section considered at a radius r from the following equation:

$$t g \alpha = \frac{r^2 \omega - C}{\sqrt{\frac{Q^2}{F^2} r^2 - C^2}}$$

20

These equations may be applied to the case when the velocity of the fluid flowing in a direction parallel to the axis is constant at all points of the entrance cross-sectional area. If, however, for any reason the entrance velocity and direction differ, this circumstance must be taken into consideration when computing. In this case the channel of the rotor must be divided e. g., into an arbitrary number of thin annular channels, and we may assume that the conditions in every one of said individual channels are identical. If the entrance velocity is not parallel to the axis, the pitch at the inlet must be correspondingly changed and the respective angular change must be maintained throughout the blade up to the outlet.

25

Such a design represents a preferred embodiment, but small deviations therefrom (within a range of ± 10 to 20 percentum) have no appreciable effect, since within said range of deviations the flowing fluid remains generally in contact with the blades. The greater the deviation, the narrower the efficient working range of the fan.

30

35

40

45

One may first determine either the shape of the blades or the cross-sectional area or shape of the channel, whereupon the cross-sectional area of the channel or the shape of the blade may be computed.

The appended drawing shows both possibilities in a largely diagrammatic manner.

The invention is illustrated in the annexed drawing in two embodiments.

Figs. 1 and 2 are axial sections through the blowers;

Figs. 3 and 4 show curves along which six cylindrical surfaces coaxial with the axis of the rotor and at distances r_1 to r_6 intersect the surface of the rotor blades;

Figs. 5-12 are sections through the blades along the above-mentioned cylindrical surfaces, the sections being developed into a plane.

In the form of construction shown in Fig. 1 the axial section through the rotor conduit has been so selected that the two limiting surfaces thereof are formed by conical surfaces which are arranged at such a distance one from the other that on the inlet side of the conduit there appears an annular surface the area of which is F_0 . F_1 is a radial plane which intersects the conduit in an annular surface the area of which is F_1 . Fig. 1 shows further in dotted lines six intersections in which six cylindrical surfaces R_1 , R_2 , R_3 , R_4 , R_5 , R_6 which are coaxial with the axis of the rotor and the respective radii of which are r_1 , r_2 , r_3 , r_4 , r_5 , r_6 intersect a vertical plane passing through the axis of the rotor. The said cylindrical surfaces R_1-R_6 intersect the surface of the rotor blades in curves A_1-A_6 shown in Fig. 3 in which the cylindrical surfaces R_1-R_6 as well as the curves A_1-A_6 are shown developed into a plane.

The tangents led in any desired point to the said curves should form with the axial direction an angle α the function $tg\alpha$ of which conforms to the above-mentioned equation. Fig. 3 shows, for instance, the tangents T_1 and T_4 led in points a_1 and a_4 to the lines A_1 and A_4 , respectively, which form with the axial direction angles α_1 and α_4 , respectively. The point a_1 lies on the cylindrical surface A_1 and the point a_4 lies on the cylindrical surface A_4 , the two points being positioned on the same radial surface F_1 .

All values appearing in the above-mentioned equation for $tg\alpha$ either are given beforehand or may be measured on the selected section of the conduit. It is possible, therefore, to calculate the angles α for any desired number of points lying in any predetermined cross-section, for instance, F_1 , and this calculation may be repeated for any desired number of radial cross-sections through the conduit. Then by interpolation it is possible to determine by this method the shape of the curves A lying on various selected cylindrical surfaces, for instance, R_1-R_6 and to define the shape of blades on basis of the points and curves so obtained.

In the embodiment shown in Fig. 4, on the contrary, the shape of the rotor blades has been selected, and Fig. 4 shows the curves in which the cylindrical surfaces R_1-R_6 intersect the surface of the blades. In this case the angles α may be measured directly, and the abovementioned equation for $tg\alpha$ permits the computation of the area of a number of radial cross-sections of the rotor conduit and thus the design of the shape of the conduit.

In both embodiments a definite channel section corresponds to a definite shape of the blades

and vice versa; there is no limitation as to the choice of one or another of these elements. The smaller the ratio of the exit sectional area to that of the entrance, the greater will be the increase in fan pressure.

A guiding apparatus L (Fig. 2) adjacent rotor R checks the whirling movement of the helical flow. Since the exit velocity is very high, a conventional conical diffuser D is preferably arranged behind the fan, said diffuser transforming velocity into pressure.

Referring to Figures 1 and 2 in detail, 1 denotes the rotor and 2 the blades. The hub of the rotor is designated 3 and the surfaces of the hub are denoted 4. 5 designates the surrounding annulus and F_1 the annular surface. The wheel axle is designated 6, and 7 denotes the guiding apparatus. 8 denotes the diffuser and 10 the limiting walls of the rotor channel in Figure 1, and 11 denotes the limiting walls of the rotor channel in Figure 2.

What I claim is:

1. In an axial flow rotary fan or pump for propelling fluids, a rotor having blades and a hub, the surfaces of the rotor hub and of the surrounding annulus and the surfaces of the blades being so shaped that a tangent led at any point to the curved line along which any cylindrical surface coaxial with the axis of the rotor intersects the surface of the blade bears the following relation to an annular surface corresponding to a section through the hub and the outer annulus and through the tangent point and normal to the wheel axis:

$$tg\alpha = \frac{r^2\omega - C}{\sqrt{\frac{Q^2}{F^2} \cdot r^2 - C^2}}$$

whereby the forces which the rotor exerts on the fluid to be conveyed cause at normal load only an increase of speed without any change of pressure.

2. In an axial flow rotary fan or pump for the propelling of gases or liquids, the combination with rotor blades driving the fluid, of a guiding apparatus checking the whirl movement of the helical flow from the rotor, and of a diffuser transforming the velocity acquired in the rotor into pressure, said rotor blades having a definite shape such that their sections with a cylindrical surface coaxial with the rotor axis stand in a definite mathematical relation to the area of the corresponding section of the rotor channel, said mathematical relation being expressed by the following equation:

$$tg\alpha = \frac{r^2\omega - C}{\sqrt{\frac{Q^2}{F^2} \cdot r^2 - C^2}}$$

3. In an axial flow rotary fan or pump for the propelling of gases or liquids, the combination with rotor blades driving the fluid, of a guiding apparatus checking the whirl movement of the helical flow from the rotor, and of a diffuser transforming the velocity acquired in the rotor into pressure, the limiting walls of the rotor channel representing converging conical surfaces providing a rapid narrowing of the initial portion of the rotor channel and thereafter but a slight diminishing of its cross-sectional area, whereas the rotor blades have a definite shape defined by the following equation:

$$tg\alpha = \frac{r^2\omega - C}{\sqrt{\frac{Q^2}{F^2} \cdot r^2 - C^2}}$$

4. In an axial flow rotary fan or pump for the propelling of gases or liquids, the combination with rotor blades driving the fluid, of a guiding apparatus checking the whirl movement of the helical flow from the rotor, and of a diffusor transforming the velocity acquired in the rotor into pressure, the limiting walls of the rotor channel representing converging arcuate surfaces providing a rapid narrowing of the initial portion of the rotor channel and thereafter but a slight diminishing of its cross-sectional area, the shape of said rotor blades being such that the tangents led to a developed cylindrical section of a blade stand in a definite mathematical relation 10 to the area of the corresponding section of the rotor channel, said mathematical relation being expressed by the following equation:

$$20 \quad \operatorname{tg}\alpha = \frac{r^2\omega - C}{\sqrt{\frac{Q^2}{F^2} \cdot r^2 - C^2}}$$

5. In an axial flow rotary fan or pump for the propelling of gases or liquids, the combination with rotor blades driving the fluid, of a guiding apparatus checking the whirl movement of the helical flow from the rotor and of a diffusor transforming the velocity acquired in the rotor

into pressure the limiting walls of the rotor channel representing converging conical surfaces providing a rapid narrowing of the initial portion of the rotor channel and thereafter but a slight diminishing of its cross-sectional area, said rotor blades being of such a shape that any tangent led to a section of the rotor blade, which section is developed by a cylindrical surface coaxial with the rotor shaft, is related to the respective sectional area of the rotor channel by the following 10 equation:

$$\operatorname{tg}\alpha = \frac{r^2\omega - C}{\sqrt{\frac{Q^2}{F^2} \cdot r^2 - C^2}}$$

wherein

$$C = \frac{Q^2}{2\omega} \cdot \left(\frac{1}{F^2} - \frac{1}{F_0^2} \right)$$

Q = quantity of air,

ω = angular velocity,

F_0 = cross sectional area of an annulus at the entrance of the channel,

F = cross sectional area of an annulus of the considered section of the channel,

r = radius of a co-axial cylindrical surface intersecting the blades.
